UNITED STATES PATENT OFFICE.

WILLIAM I. DAVIDSON, OF LONG BEACH, CALIFORNIA.

TRICK DECK OF CARDS.

Application filed May 24, 1923. Serial No. 641,090.

To all whom it may concern:

Be it known that I, WILLIAM I. DAVIDSON, a citizen of the United States, residing at Long Beach, in the county of Los Angeles 5 and State of California, have invented new and useful Improvements in Trick Decks of Cards, of which the following is a specification.

This invention relates to trick decks of 10 cards, and has for its object to provide a deck of cards of any suitable number and of any suitable suit and facial decoration.

An object is to provide a deck of cards 15 for amusement purposes by the playing of tricks, and an object is to provide a trick deck which is of extremely simple construction, and further object is to provide a method for readily converting standard decks of cards into trick decks at small expense.

20 Other objects and advantages will be made manifest in the following specification of embodiments of the invention illustrated in the accompanying drawing, wherein

Fig. 1 is a perspective showing a portion 25 of the trick deck of cards.

Fig. 2 is a longitudinal section through a number of the stacked cards.

Fig. 3 shows the performance of one of the tricks.

30 Fig. 4 is an edge view showing a modified form of the trick deck.

For purposes of illustration the present trick deck is composed of common playing cards, preferably 52 in number, and of this 35 number about one-half are all identical, and in the present case the identical cards are shown as aces of spades, and the remaining cards 2 (only a few of which are shown) are of the usual suits, 26 of the usual complete deck being discarded and 26 of the 40 identical cards, here shown as aces of spades, being substituted for the omitted 26 cards.

The identical cards designated 3 are by 45 my method cut off to make them slightly shorter than the remaining standard cards of the deck, as is clearly indicated in Fig. 2. The remaining 26 cards of the deck (or whatever number may be used) are then 50 buffed along their transverse end edges in any suitable manner, the result of which is to set up slight transverse burrs 2^a along the end edges and on each corner of the end edges.

With a deck of cards composed of these 55 two varieties, that is, a number of substantially full length playing cards and an-

other number slightly shorter, and in this case being the identic card 3, the cards are stacked in alternate positions as shown in Fig. 2, one of the shorter cards being placed 60 between two of the slightly longer cards. It will be seen, therefore, that the shorter cards will have their transverse ends practically concealed when the cards are stacked, yet the difference in the deck of cards will 65 be practically undetectable to the casual observer of the deck when the same has been stacked up as shown in Fig. 2.

A number of various tricks may be performed, one of which is clearly illustrated in 70 Figs. 2 and 3 wherein a comparatively sharp edged instrument I may be pushed against one end of the deck of cards, and it has been found from actual practice with the deck that the edge of the instrument will invariably pass between the burred edges 2^a of the suit cards 2 and will come to rest 75 against one of the shorter identic cards 3 with a result that the engaged card can be pushed upwardly from the deck. The trick 80 in this illustration consists of the fact that irrespective to the pushing of the instrument I at any apparent portion along the end of the deck one of the identic cards will be thrust into view. The observer, being uninitiated, will be astonished to find, 85 believing there is only one of the cards (as the ace of spades) in the deck, that this imagined single ace of spades may be pushed into view by the mere application of the instrument to the end of the deck in a haphazard manner.

It will be obvious, when the cards have been stacked up and the deck is held between the finger of one hand and the finger, 95 or fingers, of the other hand is pressed down upon the deck, and the latter bowed so as to cause the cards to spring to an upright position as successively released, that the shorter cards will snugly follow the released 100 leading adjacent longer card and, therefore, only the faces of the longer cards will be presented to view, and as the longer cards are springing toward the observer it will appear that the deck consists of the usual 105 suits of cards since the faces of the longer cards are displayed in various suits. Conversely, if the deck be bowed in the reverse direction then the longer cards will spring away from the former, or with their backs 110 away from observer and, therefore, the shorter cards will spring away following the

longer cards and their identic faces will be presented successively through the deck as the cards are released.

A further trick will consist in placing the cards face down, dividing the cards so as to present one of the identic cards on top of the stack and then asking the observer to observe the character of the top card which is then placed back on top of the deck.

- 10 Following this the deck is divided into a plurality of subdivisions, and if carefully done each of the top cards of the subdivisions will consist of an identic suit card, and therefore the observer will be asked to 15 select from the top of any one of the subdivisions a card, and he will find this to be one of the identic cards.

From the above it will be seen that I have provided a deck of cards for performing 20 numerous tricks and method for making same.

A slightly modified form of the deck is shown in Fig. 4 wherein instead of the cards being cut to produce two groups of 25 different lengths one-half of the deck of cards, being that half which comprises the various suits, will have their end roughened up as by sandpapering to produce a substantially burred edge ^{2b} thus practically lengthening the cards in this way to provide for the desired difference.

Further embodiments, modifications and variations may be resorted to within the spirit of the invention.

35 What is claimed is:

1. A trick deck of cards consisting of two groups which have differentiated end edges whereby when the cards of the two groups are stacked in alternate positions the end edges of one group of the cards will provide 40 means to receive pressure of the player's finger, or fingers, when applied to the end of the deck, the differentiation consisting of the deck, the differentiation consisting

in that the transverse end edges of the cards of one group are substantially burred.

2. A trick deck of cards consisting of two groups which have differentiated end edges whereby when the cards of the two groups are stacked in alternate positions the end edges of one group of the cards will provide means to receive pressure of the player's finger, or fingers, when applied to the end of the deck, the differentiation consisting in that the transverse end edges of the cards of one group are substantially burred, one of the groups of cards consisting of cards of less length than the burred cards.

3. The method of making a trick deck of cards which consists in burring the transverse ends of the cards of a group and cutting another group of cards of similar pattern and different suits to a slightly less length than of the cards of the first mentioned group.

4. The method of making a trick deck of cards which consists in cutting the cards of a group each to a predetermined dimension, and burring the transverse ends of the cards of another group, which cards have a length slightly greater than the cards of the first main group.

5. The method of making a trick deck of cards which consists in the roughening of the transverse ends of the cards of a group and cutting another group of cards of similar pattern and different suits to be of slightly less length than that of the cards of the first mentioned group after they have been roughened, but of the same length that the cards of the first group were before the roughening operation.

In testimony whereof I have signed my name to this specification.

W. I. DAVIDSON.
